UNITED STATES PATENT OFFICE.

GEORGE A. EYNON, OF PARMA HEIGHTS, OHIO.

CARBURETOR.

Application filed March 14, 1925. Serial No. 15,477.

This invention relates to carburetors and is directed more particularly to carburetors for use in connection with internal combustion engines.

5 The primary object of the present invention is to provide a carburetor wherein means are included for admitting air or other combustion supporting fluid to the fuel jet so that the fuel emerging from the 10 jet will be atomized before it is mixed with the main supply of air which carries the vaporized fuel to the engine cylinders.

Another object is to provide a carburetor which shall automatically provide a particularly rich priming mixture for starting purposes and an enriched mixture for purposes of accelerating.

20 Another object is to provide a carburetor wherein means are provided for varying the normal operating mixture proportion of fuel and air without affecting the starting mixture.

25 A further object is to provide a carburetor which shall permit the engine to run at particularly slow speeds or which shall permit rapid acceleration thereof without missing or stalling.

30 A still further object is to provide a carburetor of the aforesaid character which shall be simple in construction, inexpensive to manufacture and which shall be highly efficient in operation.

35 With these and other objects in view, the invention consists in the various novel features of construction and arrangement or combination, all of which will be fully described hereinafter and pointed out in the appended claims.

40 In the drawings accompanying and forming part of this application, Fig. 1 is a vertical sectional view through a horizontal or side outlet type of carburetor employing my invention; Fig. 2 is a vertical sectional view taken on the line 2—2 of Fig. 1; Fig. 3 is 45 a vertical sectional view through a vertical or top outlet type of carburetor showing my invention applied thereto; and Fig. 4 is a horizontal sectional view taken on the line 4—4 of Fig. 3.

50 Describing the parts by reference characters and referring particularly to Figs. 1 and 2, 1 denotes the body portion of a side outlet type of carburetor which may be in the form of a casting. This casting is provided with the usual air inlet opening 2 which communicates with a frusto-conical

passage 3 forming a venturi, and this passage in turn communicates with an outlet opening 4 which is adapted to be connected to the intake manifold of an internal combustion engine in the usual or any approved manner.

Located within the air inlet opening 2 is a choke valve 5 that is adapted to be operated from the dash or otherwise as in ordinary practice. This valve is formed 60 with a slotted opening 6 in the lower edge thereof for a purpose to be referred to hereinafter. The inlet opening 2 also has located therein an air valve 7 which is pivotally mounted on a shaft 8 located above the horizontal axis of opening 2 and the lower end of this valve is provided with a weight 9 so that the valve tends normally to remain in a vertical position. A stop pin 10 projects into opening 2 and limits the pivotal 70 movement of air valve 7. Some clearance is provided between the air valve 7 and the part of the air duct which surrounds the same whereby there may be a passage of some air at all times to the mixing chamber. 75

In Fig. 1, this clearance is shown above the top of the air valve. A throttle valve 11 of the usual type is pivotally mounted within the outlet opening 4 and this valve is formed 80 with a slotted opening 12 in the bottom peripheral edge thereof for a purpose to be referred to hereinafter.

The casting 1 is formed with a downwardly projecting stem 15 which is provided with a vertically disposed bore 16 into which is threaded a fuel nozzle 17. The upper end of bore 16 is reduced in diameter to provide a restricted jet or outlet as indicated at 18, and is formed with a seat 19 which cooperates with a needle valve 20 that is threaded in 85 casting 1 in longitudinal alignment with the bore 16. The valve 20 is provided with a suitable handle 21 to facilitate operating the same, and a slotted bushing 22 serves normally to hold the valve 20 in adjusted position. The foregoing general construction is 90 substantially standard practice in carburetors of this particular type and forms no 100 part of the present invention.

In applying my invention to a carburetor 105 of this general type I provide a bore 23 which extends through the casting 1 and communicates at one end with the air inlet opening 2 between the choke valve 5 and the air valve 7, while the opposite end of bore 110 23 communicates with bore 16 at a point below the top of the fuel nozzle 17. The por-

tion of bore 23 which communicates with the air inlet opening between choke valve 5 and the air valve 7, is provided with a plug 25 having a restricted passage 26 therethrough so as to limit the volume of air passing through bore 23 to the fuel jet 17. The restriction in the bore 23 as shown at 26 controls the supply of liquid fuel through the bore 23 when the choke valve is closed and 10 also controls the amount of air that is delivered to the bore 16 when the choke valve is open and the engine is running under normal operating conditions. This restriction is of a size to admit sufficient air to counteract the effect of the excess amount of 15 liquid fuel delivered through the nozzle 17 and has the effect of properly proportioning the liquid fuel and air in order to give the proper mixture for normal operating conditions.

The downwardly projecting stem 15 of the main casting 1 is surrounded by a float 29 and a fuel bowl 30, the latter having communication with bore 16 through an aperture 31 in the side wall of the stem 15. The float 29 is adapted to operate a float chamber inlet needle valve 32 to automatically regulate the supply of fuel to the float chamber in the ordinary manner and a detailed 25 description of this mechanism and the operation thereof is deemed unnecessary. A drain plug 33 is threaded into the lower end of stem 15 and serves to retain the bowl 30 in position and also to afford a convenient 30 means for draining fuel from the bowl as occasion demands.

In operation, the choke valve 5 is closed and the motor is rotated in the usual manner. This creates a suction in the intake 40 manifold, carburetor outlet opening 4, mixing chamber 3 and air inlet opening 2. The air inlet opening, being substantially shut off to the atmosphere by valve 5 causes fuel to be sucked through the conduit formed by 45 the bore 16 and discharge outlet 18, and also through bore 23 and discharge outlet 26. A small amount of air will be admitted through the slotted opening 6 in the choke valve 5 which will be of sufficient volume to 50 slightly atomize the raw fuel drawn into the engine cylinders and thus greatly facilitate starting of the motor. As soon as the motor starts, the choke valve 5 is opened and assumes a horizontal position as shown 55 in Fig. 1. The inrushing air through inlet opening 2 deflects air valve 7 in a counter-clockwise direction as viewed in Fig. 1, which permits a predetermined volume of air to pass through the mixing chamber 3 and outlet 4. A portion of the air will also pass 60 through opening 26 and bore 23 to bore 16 at a point below the top of the fuel nozzle 17. The air so admitted will serve to atomize the fuel ejected from the nozzle 17 and 65 hence a rich volatilized mixture will emit

from opening 18 into the mixing chamber 3 which will be further admixed with the aforementioned volume of air passing therethrough to form an explosive mixture of the correct proportion. Due to the fact that the 70 fuel is atomized when it emits from opening 18, a thoroughly atomized mixture will be insured in the mixing chamber 3 before it passes to the intake manifold and engine cylinders. The volume of preatomized mixture emitting from opening 18 may be controlled by adjusting the valve 20 toward or from its seat 19. The main volume of air passing through mixing chamber 3 is automatically governed by means of the weight- 75 ed air valve 7, the size of the venturi, and is also dependent upon the extent the throttle valve 11 is opened.

Attention is also called to the fact that the fuel nozzle 17 is normally below the fuel 80 level in the float chamber, such level being indicated by the dot-and-dash line A—A in Fig. 1. It is thus apparent that fuel normally occupies a portion of the bore 23. When the motor is idling, there will be a 85 relatively small volume of air passing through inlet opening 2 and bore 23 and hence a particularly rich mixture will be emitted from opening 18 into the main air supply passing through mixing chamber 3. 90 Under these conditions the idling mixture as a whole is enriched which is desirable in order to prevent stalling of the motor when a load is applied thereto or when running idle. As the throttle valve 11 is opened 100 to accelerate the motor, the aforementioned rich idling mixture will continue to emit from opening 18 for a brief period, or until the speed of the motor is sufficient to draw additional air through bore 23, and hence a 105 rich mixture is momentarily supplied through opening 18 which is highly desirable for purposes of accelerating. As the engine speed increases due to such acceleration, a larger volume of air will be supplied 110 through bore 23 and hence cause a leaner mixture of fuel and air to be discharged through opening 18 into the main air supply passing through the mixing chamber 3. 115 It is thus apparent that the mixture as a 115 whole will be automatically thinned out as the engine speed increases which permits economy of operation to be effected.

In Figs. 3 and 4 I have shown my invention applied to a vertical or top outlet type 120 of carburetor. In these views 40 denotes the air inlet of the carburetor, 41 the mixing chamber thereof which is formed by means of a venturi 42, and 43 denotes the outlet passage. A choke valve 44 is pivotally 125 mounted within the air inlet opening 40 and a throttle valve 45 is similarly mounted in the outlet passage 43. In this type of carburetor the float chamber 46 and associated 130 mechanism is located to one side of the main

casting 47. The float needle and associated mechanism are of standard construction usually found in this type of carburetor and a detailed description thereof is deemed 6 unnecessary.

Fuel is admitted from the float chamber 46 through a passageway 48 to a fuel jet 49 which is disposed within a vertical bore 50 formed in the main casting 47. The upper end of bore 50 is provided with a restricted aperture 51, and a valve 52 cooperates with said aperture to vary the amount of fuel or vaporized mixture (as will be explained hereinafter), which is admitted to a horizontal bore 53 that conducts such mixture to the mixing chamber 41. A vertically disposed bore 54 extends upwardly from bore 53 and the upper end of this bore communicates with a horizontally disposed bore 55 which communicates through a restricted opening 56 with the outlet passage 53 at a point adjacent the normally closed position of the throttle valve 45. A valve 57 cooperates with the restricted passage 56 to limit the opening thereof and hence form a low speed adjustment for the carburetor. In applying my invention to a carburetor of this type, I provide a bore 59 in the body portion of the casting 47, and this bore preferably communicates at one end with the mixing chamber at a point below bore 53 and above the normal fuel level in the float chamber which is indicated by the line B-B. The opposite end of bore 59 communicates with bore 50 at a point below the top of the fuel jet 49.

In operation, the choke valve 44 is closed and the motor rotated to cause fuel to be drawn from the float chamber through passage 48, jet 49, restricted passage 51 and bore 53 to the mixing chamber. Fuel will also be drawn from jet 49 through bore 59 to the mixing chamber and hence a particularly rich mixture will be supplied to the motor for purposes of starting. After the motor has been started, the choke valve 44 is opened to the position shown in Fig. 3, and air is now drawn through bore 59 and thence upwardly through bore 50. The air thus entering bore 50 admixes with the fuel withdrawn from jet 49 and hence the atomized mixture is drawn through restricted opening 51 and through bore 53 to the mixing chamber as has been previously explained in connection with the type of carburetor shown in Figs. 1 and 2.

The carburetor shown in Figs. 3 and 4 will operate in substantially the same manner as disclosed in connection with the horizontal or side outlet type of carburetor except that for purposes of idling the atomized mixture in the vertical type of carburetor will be drawn upwardly through bore 54 and discharged through restricted passage 56 to the carburetor outlet passage 43,

such discharge being permitted by means of a small opening 60 formed in the peripheral edge of the throttle valve 45 adjacent opening 56.

With a carburetor constructed in accordance with my invention, it will be apparent that the mixture adjusting valve 21 in the case of the side outlet type of carburetor or 52 in the case of the vertical type of carburetor may be adjusted for the best position for normal running conditions. When the motor is started and the choke valve closed, fuel will be admitted in the usual manner and also through the bore which communicates with the air inlet passage and the jet bore so as to supply an additional amount of fuel which is highly desirable for starting. After the motor has started, a volatilized mixture of air and fuel will be admitted from the jet and this mixture will be admixed with the main volume of air passing through the carburetor. When the motor is idling a relatively rich mixture will be supplied to the engine cylinders, and such rich mixture will be supplied momentarily when the engine is accelerated, although the mixture will be automatically thinned out as the engine speed increases. These conditions are highly desirable for the operation of an internal combustion engine in an automobile where the speed of the engine is varied rapidly to meet traffic conditions.

I have found by actual experiment that greater economy and better engine performance may be obtained by varying the volume of volatilized fuel mixture which is admixed with the main volume of air, than could be obtained by the ordinary method of varying the amount of fuel which is admixed with the main volume of air.

The purpose of the aperture 12 in throttle valve 11 is to prevent any condensation of the fuel in the intake manifold from piling up in a dead position at this point on the engine side of the throttle during idling of the engine. The aperture 12 provides a larger opening between the throttle and discharge outlet walls than is ordinarily obtained when the throttle is in idling position, hence such aperture permits sufficient air to pass at this point to prevent the aforementioned piling up of the condensation.

Having thus described my invention, what I claim is:—

1. A carburetor comprising a body portion having a mixing chamber and an air supply duct leading to said chamber, a nozzle for liquid fuel, a conduit surrounding the said nozzle and extending therefrom toward the mixing chamber, there being a restricted outlet by which the conduit may discharge into the mixing chamber, an air valve in said duct adapted to permit the passage of air at all times to said mixing chamber, there being a restricted passage for air com-

8 municating at one end with the said conduit and at its other end with the said duct on the atmosphere side of the air valve, and a needle valve adjustably controlling the delivery of fuel and air from the said outlet to the mixing chamber.

2. In a carburetor of the class described comprising a body portion, an air inlet, a mixing chamber and a mixture discharge outlet, a choke valve in said air inlet, a constant level fuel supply chamber, a bore connecting said fuel supply chamber with said mixing chamber, a fuel discharge nozzle positioned within said bore and below the normal level of fuel therein and adapted to deliver fuel in excess of the normal requirements, a conduit connected at one end with said bore and at the opposite end with said air inlet on the suction side of said choke valve, said conduit having a restriction therein whereby to limit the supply of air to said bore when said choke valve is open, said conduit also serving as an additional fuel supply to said mixing chamber when said choke valve is closed, said bore having a needle valve adjacent the delivery end thereof for controlling the volume of mixture delivered to said mixing chamber through said bore.
3. A carburetor of the class described comprising a body portion having an air inlet, a mixing chamber, and a mixture discharge outlet, a choke valve in said air inlet having

9 a slotted opening therein, an air valve in said air inlet adapted to permit the passage 35 of air at all times to said mixing chamber, a fuel supply chamber and a conduit connecting said fuel supply chamber and mixing chamber, a restricted passageway communicating with said conduit at one end and at 40 the opposite end with said air inlet on the engine side of said choke valve.

4. A carburetor comprising a body portion having a mixing chamber, an air supply duct having a choke valve therein and a mixture 45 discharge outlet, a nozzle for liquid fuel, a conduit surrounding said nozzle and extending therefrom toward said mixing chamber, there being a restricted outlet by which said conduit may discharge into said mixing 50 chamber, an air valve in said air supply duct adapted to permit the passage of air at all times to said mixing chamber, a restricted passage communicating at one end with said conduit and at the other end with said duct 55 on the engine side of the choke valve whereby said passage will serve to convey fuel to said mixing chamber when said choke valve is closed and will serve as an air supply to said conduit when said choke valve 60 is open and a needle valve adjustably controlling the delivery of fuel and air mixture from said conduit into the mixing chamber.

In testimony whereof, I hereunto affix my signature.

GEORGE A. EYNON.
